UNITED STATES PATENT OFFICE

146,359

DESIGN FOR A COMBINATION KEY HOLDER AND LIGHT

Arthur C. Holmberg, Minneapolis, Minn.

Application May 11, 1946, Serial No. 129,603

Term of patent 3½ years

(Cl. D17—14)

To all whom it may concern:

Be it known that I, Arthur C. Holmberg, a citizen of the United States of America, residing at Minneapolis, in the county of Hennepin and State of Minnesota, have invented a new, original, and ornamental Design for Combination Key Holder and Light, of which the following is a specification, reference being had to the accompanying drawing, forming part thereof.

Figure 1 is a plan view of a combination key holder and light, showing my new design;

Figure 2 is a front end view;

Figure 3 is a side elevational view; and

Figure 4 is a rear end view.

I claim:

The ornamental design for combination key holder and light, as shown.

ARTHUR C. HOLMBERG.
